ELECTRICAL CURRENT CONTROLLING MECHANISM

Application filed March 10, 1931. Serial No. 521,568.

This invention relates to an electrical current controlling mechanism and has for its object to provide, in a manner as hereinafter set forth, a mechanism of the class referred to for intermittently flashing an illuminable means of that type consisting of a transparent or translucent element containing a body of neon, argonne, helium, etc.

A further object of the invention is to provide, in a manner as hereinafter set forth, a self starting, automatic contact combination current control for high frequency gas tube illumination employing neon, argonne, helium, et al.

15 A further object of the invention is to provide, in a manner as hereinafter set forth, a mechanism for the purpose referred to which is extremely durable, of low current consumption, satisfactory in operation and not requiring any attention for a long period of time.

Further objects of the invention are to provide, in a manner as hereinafter set forth, an electrical current controlling mechanism which is simple in its construction and arrangement, strong, durable, compact, thoroughly efficient in its use, self starting, readily assembled, and comparatively inexpensive when used.

30 With the foregoing and other objects in view, the invention consists of the novel construction, combination and arrangement of parts as hereinafter more specifically described, and illustrated in the accompanying drawing, wherein is shown an embodiment of the invention, but it is to be understood that changes, variations and modifications can be resorted to which fall within the scope of the claims hereunto appended.

40 In the drawing wherein like reference characters denote corresponding parts throughout the several views:—

Figure 1 is a side elevation of an electrical current controlling mechanism in accordance with this invention.

Figure 2 is a front elevation thereof.

Figure 3 is a top plan view thereof.

Figure 4 is a diagrammatic view illustrating the circuit arrangements.

50 In the diagrammatic showing Figure 4, a

vibratory armature of conducting material is indicated at A, a vibrating member of conducting material at B, a primary coil at C, the core for the coil C at D, a secondary coil E connected to an illuminable element F, a battery G, a governor control magnet H which is associated with the armature A, a condenser I, a governor control weighted spring controlled oscillatory bar J, a contact K on the shaft J which is associated with armature A, 60 a circuit connection L from magnet H to shaft J, a circuit connection M from battery G to magnet H, a circuit connection N from battery G to armature A, a circuit connection O between connection N and condenser I, an adjustable contact piece B' carried by armature A, and a circuit connection M' from connection M to coil C, and a circuit connection R from coil C to member B.

Referring to Figures 1, 2 and 3 of the drawing, Q denotes a casing in which is arranged the elements C, D, E, F, G, I, M', M, N, O, R. The element H is arranged upon the top of casing Q. Element R leads to condenser I. Mounted on casing Q is a bearing tube S for 75 a vertically disposed governor shaft T which extends through the governor bar J, the latter having at each end a weight indicated at J', J''. The tube S is threaded at its upper end at S'. Attached at one end to the upper end of shaft T is a spiral spring U. The other end of spring U as the latter is attached to an adjustment bracket V connected to the tube S and maintained in adjusted position by a nut S'' engaging the threads S'. The 80 bar J in proximity to the weight J'' is provided with the contact K. Extending through the lower portion of armature A and engaging with casing Q is a screw A' provided with an adjustable stop nut A'' for controlling the outward swing of the lower portion of the armature which abuts the outer face of armature A. The armature A intermediate its ends above screw A' is provided with an adjustable contact piece B' for engagement with a contact piece B'' carried by the vibratory member B. Riveted to the top of magnet H and projecting outwardly therefrom is a screw H' which extends through armature A and carries an adjustable stop 95 100

nut H'' which opposes the outer face of armature A for controlling the outward swing of the upper portion of the armature. The latter freely vibrates on screw H'. The armature A is provided with a plate C' opposing the core of the magnet H. The upper end of armature A is in the form of a spring blade C'' which vibrates freely.

To describe the device in general, we have 10 a governing swinging balance bar with a spiral spring, adjustable for speed variation, carried by a shaft set in a sleeve, the bar is actuated by an armature that is drawn toward a magnet, the armature bar terminating 15 in an adjustable spring contact, that when it comes in contact with the governing bar which also carries a contact, closes the current and whips the governing bar away from contact causing it to release. This operation 20 is continuous as long as current is supplied.

Current entering magnet H of governor travelling through governor bar J held in contact to upper point of armature spring blade C'' by the spiral spring U. The spring 25 U also acts as a speed regulator for the governor and maintains the electrical contact between the governor bar J and the upper point of armature spring blade or plate C'' at all times until the magnet H receives the 30 current.

At this time current energizes the magnet H drawing armature plate C' toward the magnet H, thus pressing the flexible contact blade C'' in reverse action against the governor bar J throwing the counter-balance weight J'', thus breaking the electric connection 35 between armature blade or plate C'' and the governor bar which relieves the magnetic throw.

40 The direction of travel of the governor bar J is reversed and brought back to another contact by the spring U to the flexible contact blade C'' at the upper end of armature A. The spring U serves as a timing element 45 governing the time of the magnet pressure on the governor bar J. When in contact, the current is passing to the governor magnet H until the armature contact blade C'' has reversed the direction of travel of the governor 50 nor weights. When this contact is broken the armature plate C'' falls back to its ready position for the next contact by the governor bar J which energizes the governor magnet H thus delivering the next magnetic throw of 55 the governor.

The adjustment screw H' serves as a regulator for the amount of magnetic throw of the governor when drawn by magnet H. Adjustment screw H' acts as a refining adjustment for the after vibration of the armature A when releasing the governor contact and the magnetic throw of the governor bar J.

High tension current contact point adjustment screw B' mounted and carried by armature A serves as a regulator. The length of 60

time contact piece B' engages with contact piece B² determines the length of time which current is drawn from the battery.

High frequency coils operate on the same general principles as follows: The primary coil is wound on an iron core which when current is passed through it magnetizes the core and if we place an iron or steel bar close to the core it will be attracted to it as long as the current is on. 70

One end of the coil is connected to an iron or steel bar and a stationary member is placed close to it and connected to the battery as shown, and then press the two bars together we will have the same result with the added 75 operation that if properly mounted the closest bar to the core will vibrate for the reason that when they are together a contact is made and the near bar is attracted to the core which opens the circuit and allows the bar to come 80 back to the stationary member and cause contact thus keeping up the vibrations as long as the current passes between the points. 85

To produce high frequency electricity which is very high in voltage but very low in amperage, a coil called a secondary coil is wound over the primary coil the wire used being very much smaller and many more turns of wire being used. 90

Then because of its peculiar properties 95 we place a condenser between the lines connecting points A and B Figure 4, for reducing sparking to prevent the destruction of the contact points. Now, in order to so operate these points so that their operation does not depend at all upon their own action by the current being turned through the primary coil through A and B we adjust B to give the greatest vibrating efficiency and operate A 100 automatically by our governor control as shown. In standard practice the points A and B are always together waiting for the electric current to separate them while in our case A and B are always apart waiting 105 for an outside agency to contact them at given intervals to produce illumination. 110

By this method any non-conducting or foreign matter that might lodge between the points and terminate the electrical action is 115 wiped out by reason of A being operated independently and in consequence we are able to make an adjustment that will pass a very low current. One will readily see that if for any cause the points A or B are held apart 120 or do not make contact for any reason, such as foreign matter getting between them or a self created crust, there will be no electrical action whatever and by reason of no current passage, there can be no method of dislodging 125 the element causing trouble. Also it will be noted that in case of these points fusing or sticking together for any reason a short will be caused through the primary winding which will discharge the battery at once and 130

no doubt ruin the coil by the resultant heat caused by the short.

The low current discharge and its low illumination is sufficient for our needs providing it will continuously function and give service for a period of months.

This is what we have accomplished by our method of operating the A member from an outside source of power.

10 We have a vibrating member B and a member A that is stationary but it has thereon a contact that is not in contact with the vibrator.

Now by a mechanical operation, we bring 15 a pressure on A that causes it to contact with the vibrating part only so long as the pressure is against it. Both vibrator and stationary parts are ready to operate, being energized. In other words, by this method, we are able 20 to produce a finer adjustment of current consumption and at the same time control the duration of the production of high frequency current and at the same moment by mechanical means, bring contact points together. It 25 can be readily seen that by this method the contacts are self repairing. In the old method, a piece of foreign substance or a non-conductor of electricity between the points would render the functioning of the coil use- 30 less for no current could pass between the points so obstructed, while by our method the object causing trouble would be dislodged or pounded out in a very short time and thus the coil would again resume operations.

35 It will be noted that the current passes from A to B which must be closed, and should any foreign substance or non-conductor of electricity become lodged between these A and B points the operation ceases. A switch is necessary 40 in the line to start and stop the operation of the vibrating member, while with our mechanism A and B are always open and are closed only by an armature member which is self-acting and when pressed together will 45 act. Our device therefore makes for finer adjustments using lower current consumption with no possibility of contact points failing to function. In the old method the points are self-actuating and therefore liable to fail 50 for many reasons.

The contact B' when engaged with the B member produces a vibrating current, it is not in any sense of the word a make and break system which produces only a single 55 spark when the contacts are made.

It is not like a high tension coil operated as in an automobile because in that case a connection is made that in turn causes the current to flow through the coil and if the points A 60 and B are clean they will vibrate and cause a high frequency spark, while we in our operation make the direct contact mechanically on the B member by a mechanical operation of the A member and thereby causing a spark 65 even if the points A and B are fouled, because

we wipe away the obstruction by the action.

The mechanism will be used in conjunction with batteries either dry or storage and as a self contained complete operating unit such as boulevard stop signs, railroad crossings, 70 danger, slow and many uses where signalling is desired, it can be used to indicate boundaries on aviation fields, navigation signals, etc.

It operates on from 2½ volts to 12 and as 75 low a discharge as 100 milliamperes thereby giving a life of many operating months without attention. It can be set to flash from fifteen to seventy times per minute and the duration of the flash can be set from one tenth 80 second to one or more seconds.

The construction and arrangement of the mechanism provides for three circuits one for the secondary, another for the primary or coil and the other for the governor magnet. Then 85 further the arrangement takes the coil operating current load off the contact points which operate the governor.

What we claim is:—

1. An electrical current controlling mechanism comprising, a primary coil functioning 90 both as the primary of an induction coil and also as a vibrator coil, a secondary coil functioning as the secondary of the induction coil, said primary coil being inductively coupled to said secondary coil, a core for the primary coil, a 95 resilient vibratory member of conducting material opposing and normally spaced from said core, said member having one end free and its other end anchored, an electro-magnetic device spaced from the primary coil and 100 including a resilient vibratory armature of conducting material opposing and permanently spaced from said member, said armature having one end anchored and its other end free, the free end of said armature being ex- 105 tended beyond said device, an electrical source, a circuit connection between one side of said source and said device, a circuit connection between the said connection and said primary coil, a circuit connection between 110 said primary coil and said vibratory member, a circuit connection between the other side of said source and said armature, a contact piece carried by said armature for intermittently engaging said vibratory member, 115 and a spring controlled governor including a contact in circuit with said device for intermittently engaging the free end of the armature for intermittently closing the circuit of 120 said magnetic device to intermittently energize the latter thereby moving the armature towards said device to cause the contact piece to intermittently engage said vibratory member to provide for the vibration of the latter thereby making the induction coil intermit- 125 tently active.

2. An electrical current controlling mechanism comprising, a primary coil functioning both as the primary of an induction coil and also as a vibrator coil, a secondary coil func- 130

tioning as the secondary of the induction coil, said primary coil being inductively coupled to said secondary coil, a core for the primary coil, a resilient vibratory member of conducting material opposing and normally spaced from said core, said member having one end free and its other end anchored, said member having a contact mounted thereon on the side opposite the core, an electro-magnetic device spaced from the primary coil and including a resilient vibratory armature of conducting material opposing and permanently spaced from said member, said armature having one end anchored and its other end free, the free end of said armature being extended beyond said device, an electrical source, a circuit connection between one side of said source and said device, a circuit connection between the said connection and said primary coil, a circuit connection between said primary coil and said vibratory member, a circuit connection between the opposite side of said source and said armature, a contact piece carried by said armature for intermittently engaging the free end of the armature for intermittently closing the circuit of said magnetic device to intermittently energize the latter thereby moving the armature towards said device to cause the contact piece to intermittently engage said member to provide for the vibration of the latter thereby making the induction coil intermittently active, and stationary, independently, adjustable, spaced stop devices extending through and abutting the outer side of the armature for controlling the outward swing of the upper and lower portions of the latter.

In testimony whereof, we affix our signatures hereto.
